(57) **CLAIM**

The ornamental design for a MOG limiting subassembly for combine concave, as shown and described.

DESCRIPTION

FIG. 1 is a first perspective view of a MOG limiting subassembly for combine concave in a deployed position; FIG. 2 is a second perspective view thereof;

FIG. 3 is a third perspective view thereof;

FIG. 4 is a fourth perspective view thereof;

FIG. 5 is a front elevation view thereof, the rear elevational view being a mirror image thereof;

FIG. 6 is a left-side elevation view thereof;

FIG. 7 is a right-side elevation view thereof;

FIG. 8 is a top plan view thereof;

FIG. 9 is a bottom plan view thereof;

FIG. 10 is a first perspective view of a MOG limiting subassembly for combine concave in a retracted position; FIG. 11 is a second perspective view thereof;

FIG. 12 is a third perspective view thereof;

FIG. 13 is a fourth perspective view thereof;

FIG. 14 is a front elevation view thereof, the rear elevational view being a mirror image thereof;

FIG. 15 is a left-side elevation view thereof;

FIG. 16 is a right-side elevation view thereof;

FIG. 17 is a top plan view thereof; and,

FIG. 18 is a bottom plan view thereof.
